CLAIM

The ornamental design for a paddle tennis court building element, as shown and described.

DESCRIPTION

FIG. 1 is a perspective view of a paddle tennis court building element, showing my new design;
 FIG. 2 is a top view thereof;
 FIG. 3 is a side view thereof;
 FIG. 4 is another side view thereof, from a side adjacent to view FIG. 3;
 FIG. 5 is an enlarged side view of the inset of FIG. 4; and,
 FIG. 6 is a cross-sectional view sectioned through the frontal plane of enlarged side view of FIG. 5.
